UNITED STATES PATENT OFFICE.

DE WITT C. MORRIS, OF NEW YORK, N. Y., ASSIGNOR TO FRANCIS KEIL & SON, OF NEW YORK, N. Y.

SHOW-CASE CORNER.

1,107,694.

Specification of Letters Patent. Patented Aug. 18, 1914.

Application filed August 24, 1911. Serial No. 645,883.

To all whom it may concern:

Be it known that I, DE WITT C. MORRIS, a citizen of the United States of America, and a resident of New York, in the county 5 and State of New York, have invented a certain new and useful Show-Case Corner, of which the following is a specification, the same being a full, clear, and exact description of the invention, such as will enable 10 others skilled in the art to which it appertains to make and use the same.

This invention relates to articles designed for purposes of exhibition, as a case or enclosure of which all or some of the sides are 15 of glass, intended to keep small and delicate or valuable objects from dust and injury while leaving them in plain sight, and in particular to an adjustable metallic corner piece, which may be clamped to the plate 20 glass sides of the show case at the corners thereof, and whereby the plate glass top or cover may be rigidly secured to the said show case.

With this object in view, the invention 25 consists in certain novel features of construction and arrangement of parts.

In order to enable the invention to be 30 fully understood, I shall proceed to explain the same by reference to the drawings illustrative of one embodiment of the invention, which accompany and form a part of this specification, and in which—

Figure 1 represents a perspective view of 35 a show case in which my invention is embodied, Fig. 2 is a bottom view of a corner thereof; and Fig. 3 is a transverse section taken diagonally across my show case corner.

Like letters of reference indicate like 40 parts in all the views.

Referring particularly to the drawing B, C, denote the glass side and end of a show case, and A the plate glass top or cover of the same. One member of body portion of 45 the corner piece is preferably made in the form of a right angle, and has two depending walls b, c, b', c' forming a channel or groove in which, when the corner piece is applied to the show case, are contained the 50 glass side plates. Screws c², b² cushioned as at c³, b³ at their interior ends are passed through the inner wall of the corner piece and serve to securely clamp the body portion 55 of the corner piece to the said side plates without producing enough pressure to crack

the glass. The said member of the corner piece is formed at the central part of the upper face thereof with an undercut groove having edges b⁴, c⁴, and also has at the central part of the top edge a shoulder formed 60 at each side of the same. The other member or top portion of the corner piece consists preferably of a clamping plate comprising a triangular part a adapted to fit and to pass over the sides, top and bottom of a corner 65 of a glass plate. The bottom part a' of the said member is extended in an inward direction, the side edges of the same being beveled so as to work in the groove of the body member, and the outer lower portion of the 70 top member is also ordinarily formed with a shoulder a⁴. The said laterally or inwardly extending bottom portion a' is also formed with a depending portion a⁵ through which passes a screw a⁶. 75

In operation, a body portion of the corner piece is attached to each of the four corners of the show case, and the top members are inserted in the same, and the corners of the plate glass top are then loosely placed in the 80 said top portions, after which the said top members of the corner clamps are adjusted by manipulating the screws a², in order to accommodate glass plates of varying sizes, from within the show case; which operation 85 serves to firmly clamp the plate glass top within the four top portions of the corner pieces which are held securely to the body portion thereof in the manner described.

Although in the embodiment shown, the 90 show case corner is only adapted to be used with a square show case, yet it is manifest that the invention may be readily adapted to show cases of other forms or contours by those skilled in the art. 95

I wish it to be understood that I do not desire to be limited to the exact details of construction shown and described, for obvious modifications will occur to persons skilled in the art. 100

What I claim is:—

In a device of the class described, a corner member having a central body portion and a channel formed by parallel depending flanges to receive the side abutting plates, 105 intermediately located cushioned device to lie between the inner flanges and the side plates, in combination with another corner member the top of which covers the top plate and the lower part whereof is flush with the top 110

face of the first member, and adjustable means located at the interior corner of the show case to engage both of the said members whereby, by one operation alone thereof, the cushioning devices may be forced with an outward pressure against the side plates, and the top plate may be held to the side plates with an inward pressure, the three plates being thereby securely fastened together without unduly straining the same,

the pressure being distributed along the edges of the plates in lieu of being localized.

In testimony of the foregoing specification I do hereby sign the same in the city of New York, county and State of New York, 15 this 28th day of July, 1911.

DE WITT C. MORRIS.
